UNITED STATES PATENT OFFICE.

WOLF T. GOLDSMITH, OF NEWARK, NEW JERSEY.

DESIGN FOR A HAND-BAG FRAME.

Application filed June 14, 1927. Serial No. 22,424. Term of patent 3½ years.

To all whom it may concern:

Be it known that I, WOLF T. GOLDSMITH, a citizen of the United States, and a resident of Newark, in the county of Essex and State of New Jersey, have invented a new, original, and ornamental Design for a Hand-Bag Frame, of which the following is a specification, reference being had to the accompanying drawing, forming part thereof.

I claim:

The ornamental design for a hand bag frame, substantially as shown.

WOLF T. GOLDSMITH.
